UNITED STATES PATENT OFFICE.

EDMUND H. WALKER, OF NEW YORK, N. Y.

DRAFT GEAR.

Application filed March 29, 1924. Serial No. 702,795.

The invention relates to friction draft gear for railway cars, and has for its principal object the provision of means adapted to prevent the incorrect assembly of the several friction members or wedge blocks with respect to the friction box.

Another object of the invention is to provide a friction draft gear in which the usual friction wedge blocks positioned in the friction box, in addition to being designed to permit clearance of the blocks upon full closure of the gear, are also provided with means for facilitating correct assembly, said means involving cooperating portions upon the wedge blocks disposed so as to interlock the same while at the same time permitting of their relative frictional sliding movement.

A further object of the invention is to provide a strong and durable friction draft gear in which the several parts can be easily and correctly assembled, the means preferably utilized to insure the correct assembly of the several friction wedge blocks involving cooperating projections and recesses provided respectively on adjacent portions of said blocks.

In the drawings chosen to illustrate the invention, the scope whereof is pointed out in the claims:

Figure 1 is a plan view illustrating the friction draft gear positioned in a railway draft rigging.

Figure 2 is a detached view of the friction draft gear in side elevation, with a portion thereof shown in section.

Figure 3 is an end view from the left hand side of the draft gear shown in Figure 2.

Figure 4 is a detail illustration of the spring barrel or casing viewed from the closed end thereof and having a portion shown in section.

Figure 5 is a sectional elevation of the center wedge block or friction member.

Figure 6 is a view of one end of the block shown in Figure 5, a portion of the block being shown in section.

Figure 7 is a top plan view, with portions in section, of the center wedge block, on the line 7—7 of Figure 5.

Figure 8 is a side elevation of one of the cooperating or outer wedge blocks.

Figure 9 is an end elevation of the block

shown in Figure 8 viewed from the right hand side.

Figure 10 is a detail cross sectional view showing adjacent portions of the coacting wedge blocks slidably interlocked through their tongue and groove connection.

Referring to the drawings in which similar reference characters designate corresponding parts in the several views, I have shown my invention applied to a friction draft gear inserted within a railway draft rigging involving the horizontal two-key Farlow construction. The center sills 1—1 are each provided with cheek plates 2, said sills and cheek plates being suitably slotted to permit relative movements of the keys 70 in the usual manner. Positioned between the sills is a horizontal yoke 3, the forward ends of the yoke arms being slotted to receive the key 4 which connects the coupler 5 with the yoke, and also extended into the aligned slots of the sills and cheek plates. Another key 6 extends through the second series of slots in the sills and cheek plates, said second named key also passing through slots provided in the yoke arm and the follower block 7 interposed between the butt of the coupler and the friction device. A rear stop member or back stop 8 is provided with which the rear of the yoke contacts.

The draft gear or cushioning mechanism 85 comprises a spring barrel or casing 9 to one end of which is applied the friction box or head 10. The friction box is of rectangular form and is provided with inclined friction faces 11 adapted to cooperate with adjacent portions of the outer friction members or wedge blocks 12. The center friction member or wedge block is indicated by the numeral 13 and positioned therebetween and the cushioning springs 14 is the follower 90 member 15 against which the springs bear.

The friction face upon which the rib 16 is provided extends beyond said rib upon one side thereof, the adjacent portion of the corner portion of the block being cut away as indicated at 17. The extending friction face and adjacent cut-away portions of the outer wedge blocks are so arranged that the respective stepped portions of the block interlock and have relatively large clearance 100 for permitting the full closure of the gear and the contacting of the follower with the friction box for imparting the excessive loads 105

to the casing and in turn to the back stop. This construction of wedge block forms a better guide on the follower and effectively keeps the block from tipping or canting.

- 5 The center friction member or wedge block 13 is provided with oppositely inclined friction faces cooperating with the adjacent surfaces of the outer wedge blocks, said inclined faces each being provided with a 10 groove or recess 18 into which fits the rib on the adjacent wedge block. The grooves or recesses in the center wedge extend the full length of the friction faces and terminate in the end wall portion against which 15 the follower of the draft rigging bears. The follower 15 contacts the other end face or wall of the center wedge member, as best shown in Figure 2. The coacting projection and depression of the respective wedge 20 blocks are preferably rectangular in cross section, the opposite side walls of the recess and rib being slightly inclined with respect to the base of the groove and the edge of the rib, such as shown in Figure 10.
- 25 In assembling the wedge blocks, it will be observed that the interlocking or interengaging portions prevent the positioning of the outer wedge blocks in any other manner than with the smooth outer friction faces 30 contacting the inclined surfaces 11, the projecting ribs 16 of said blocks being caused to enter the correspondingly shaped grooves or depressions 18, thus permitting the several blocks to move with relation to each 35 other for developing maximum frictional resistance.

While I have shown the wedge blocks as provided with single interengaging means, it will be understood that more than one rib 40 or other similar portion may be provided, and I do not wish to be understood as limiting the invention to the exact disclosure herein. The several wedge blocks are preferably cast hollow, as shown. Friction 45 wedge members constructed in accordance with the present invention are comparatively inexpensive to manufacture and may be very rapidly assembled within the friction box and maintained in interlocked and 50 sliding relation, while at the same time being capable of their usual operation for developing maximum friction. It will also be understood that the improved method of interengaging the several friction blocks can be accomplished without departing from the usual standards of measurement required in 55 draft gear construction.

I claim:—

- 60 1. A friction shock absorbing mechanism for railway draft rigging involving a spring barrel, a friction box positioned at one end of said barrel, a spring mounted within said barrel, a plurality of wedge blocks cooperating with the friction box, a center wedge block, and means disposed along opposite

sides of the center wedge block adapted to interengagingly coact with an adjacent portion of each of the first named wedge blocks, said means serving to facilitate correct assembly thereof.

70

2. A friction shock absorbing mechanism for railway draft rigging involving a spring barrel, a rectangular friction box positioned at one end of the barrel and having oppositely disposed inclined friction faces, a 75 spring mounted within said barrel, a plurality of cooperating wedge blocks, the outermost of said blocks having portions contacting the inclined friction faces of the friction box, and the intermediate wedge block 80 having portions coacting with adjacent portions of the outer wedge blocks for facilitating correct assembly of the blocks, all of said wedge blocks being relatively movable.

85

3. A friction shock absorbing mechanism for railway draft rigging involving a spring barrel, a rectangular friction box positioned at one end of the barrel and having oppositely disposed inclined friction faces, a 90 spring mounted within said barrel, friction wedge blocks having portions cooperating with the friction box, each of said blocks having a projecting portion, and a center wedge block having portions coacting respectively with said projecting portions for 95 facilitating correct assembly of the several wedge blocks.

90

4. A shock absorbing mechanism of the class described including in combination a friction box having inclined friction faces, 100 a cushioning element, a casing surrounding said cushioning element and engaging said friction box, a plurality of friction blocks having portions engaging the inclined friction faces of the friction box, a wedge block 105 interposed between said friction blocks, and means including coacting projections and recesses for interlocking said wedge and friction blocks.

100

5. A shock absorbing mechanism of the 110 class described, the combination with a friction box having inclined friction faces, a cushioning element, a casing surrounding said cushioning element and engaging the friction box, a plurality of friction blocks 115 having their outer faces engaging the inclined faces of the friction box, the inner faces of each of said friction blocks being provided with a projection, and a friction wedge block coacting with said friction blocks, said friction wedge block being provided with depressions adapted to slidingly receive the projections on said friction blocks.

115

6. A wedge block for friction draft gear 125 having a plurality of friction surfaces, one of said surfaces being provided with means adapted to coact with means on an adjacent block for interfittingly engaging the same therewith, said wedge block having a stepped 130

portion formed by continuing a portion of one of said friction surfaces beyond the aforesaid means and cutting away a portion of the block adjacent the continued friction surface.

5 7. In a friction draft gear including a friction box having inclined friction surfaces, and outer and inner wedge blocks coacting with said surfaces and with one another, the outer wedge blocks each having one corner adjacent the inner wedge block cut away at one side to define a stepped portion, the step wall opposite the adjacent surface of the inner wedge block being inclined outwardly away from the longitudinal center line of the gear.

10 8. In a friction draft gear including a friction box having inclined friction surfaces and a center wedge; friction blocks 20 interposed between and coacting with the center wedge and friction box, each of said friction blocks having a corner adjacent the center wedge cut away at one side, one wall of the cut away portion lying in a plane 25 longitudinally of the block and the other extending at an angle with respect to a horizontal plane passing through the longitudinal center of the gear.

15 9. In a shock absorbing mechanism of the 30 character described, a spring barrel, a friction box at one end thereof having oppo-

sitely inclined friction surfaces, cushioning means within the spring barrel, a pair of friction blocks having inclined outer surfaces coacting with the inclined surfaces of the friction box and likewise having inclined inner surfaces, and a wedge block interposed between and contacting with said friction blocks, the adjacent ends of the friction blocks having their diagonally opposite 40 corners formed in stepped relation.

10 10. In a shock absorbing mechanism of the character described, a spring barrel, a friction box at one end thereof having oppositely inclined friction surfaces, cushioning means within the spring barrel, a pair of friction blocks having inclined outer surfaces coacting with the inclined surfaces of the friction box and likewise having inclined inner surfaces, a wedge block interposed between and contacting with said friction blocks, the adjacent ends of the friction blocks having their diagonally opposite corners formed in stepped relation, and the contacting faces of the friction blocks and wedge block being formed with interfitting ribs and grooves, said stepped portions and the ribs and grooves facilitating correct assembling of the parts.

15 In testimony whereof I affix my signature.

EDMUND H. WALKER.
